UNITED STATES PATENT OFFICE.

EDWARD POSSON, OF CHICAGO, ILLINOIS.

ANGLE-COCK HOLDER.

1,083,337.

Specification of Letters Patent.

Patented Jan. 6, 1914.

Application filed September 20, 1913. Serial No. 790,886.

To all whom it may concern:

Be it known that I, EDWARD POSSON, a citizen of the United States, residing at Chicago, in the county of Cook and State 5 of Illinois, have invented certain new and useful Improvements in Angle-Cock Holders; and I do hereby declare the following to be a full, clear, and exact description of the invention, such as will enable others 10 skilled in the art to which it appertains to make and use the same.

My invention has for its object to provide a simple and efficient angle cock holder for holding the angle cock on the train pipe of 15 a car in proper position and always at the proper angle.

Generally stated, the invention consists of the novel devices and combinations of devices hereinafter described and defined in 20 the claims.

In the accompanying drawings which illustrate the invention, like characters indicate like parts throughout the several views.

Referring to the drawings: Figure 1 is 25 a view showing a box car in end elevation and showing my improved angle cock holder applied thereto; Fig. 2 is a side elevation showing a part of the car body, the angle cock holder, train pipe and angle cock in 30 side elevation; Fig. 3 is a section taken on the line $z^2 z^3$ on Fig. 2; and Fig. 4 is a front elevation of the angle cock holder with the angle cock and train pipe removed.

The numeral 1 indicates the car body. 35 The numeral 2 the train pipe and the numeral 3 the angle cock which is screwed onto the end of the said train pipe. This angle cock 3 has the usual nut-equipped end 4 surrounding the end of the train pipe onto 40 which it is screwed. A lock collar or sleeve made up of a U-shaped body 5 and heads 6, is slipped onto the end of the train pipe 2 before the angle cock is screwed onto the said pipe. The front or outer head 6 is, as 45 shown, made hexagonal to correspond to the nut surface 4 of the angle cock, and it is provided with several, as shown, with three laterally projecting lock flanges 7 that engage with the nut surfaces 4 of the said 50 angle cock, to thereby positively lock the said angle cock and collar against rotation, the one in respect to the other. This collar is supported from the car body by a hanger bracket 8 and co-operating clamping cap or 55 bar 9 secured thereto by nut-equipped bolts 10. The hanger bracket 8 is formed with a

lateral bulge 8^a, and in line with the upper and lower extremities thereof, the clamping bar 9 is formed with notches 9^a, and between said notches with a segmental concave clamping lug 9^b. When the collar is applied in the hanger bracket, the heads 6 thereof will be located, one inward and one outward of said bracket, and the extremities of its U-shaped body 5 will project into 65 the notches 9^a of the clamping bar 9, while the clamping lug 9^b will extend into the said U-shaped portion and into engagement with the train pipe, so that the train pipe will be firmly clamped between the said lug and 70 the said U-shaped body portion. The collar is thus, when the bolts 10 are tightened, held against rotation as well as against endwise displacement. To further insure this action against rotation, the U-shaped body portion 75 5 of the collar is shown as provided with bearing lugs 5^a that fit within the bulged portion 9^b of the hanger bracket.

Of course, the flanges 7 on the front head of the pipe supporting collar must be so 80 located, in respect to the projecting flanges of the U-shaped body 5, as to cause the angle cock to be set in its proper or desired position, which is assumed to be thirty degrees to a vertical. Obviously, when the train 85 pipe and angle cock are held, as above just described, and, as shown in the drawings, there is no possibility of either angle cock or the train pipe being rotated. Hence, the angle cock will always be at the right angle 90 for use and cannot possibly work itself loose from the train pipe, but nevertheless, when desired, it is an easy matter to remove the clamping bar 9, and then to slip the lock collar back on the train pipe, so that the 95 angle cock may be screwed off from the train pipe.

What I claim is:

1. An angle cock holder comprising a supporting bracket and a lock sleeve held therein, said bracket having a clamping bar for securing said collar thereto, and said collar having flanges engageable with the nut end of the angle cock to hold the same against rotation. 100

2. The combination with a hanger bracket having a clamping bar provided with a clamping lug, of a lock sleeve having a U-shaped body and flanged heads, said U-shaped body being held in said bracket with 110 its open side opposite to said clamping lug, and one of the flanged heads of said lock

collar having flanges for interlocking engagement with the nut end of an angle cock applied to a train pipe when said train pipe is passed through said lock collar.

5 3. The combination with a hanger bracket having a clamping bar and bolts adjustably connecting the same thereto, said bracket having a bulged intermediate portion and said clamping bar having a clamping lug 10 opposite thereto, of a lock sleeve having flanged heads and a U-shaped body, said U-shaped body being insertible into the bulged portion of said bracket in line with the said clamping lug, and

one of the flanged heads of said lock sleeve having lock flanges adapted to engage the nut end of an angle cock, applied to the end of a train pipe which has been passed through said collar and is clamped between the U-shaped body thereof and the opposing 20 clamping lug of said clamping bar.

In testimony whereof I affix my signature in presence of two witnesses.

EDWARD POSSON.
